UNITED STATES PATENT OFFICE.

JOHN O. NEIKIRK, OF MORGAN PARK, ILLINOIS, ASSIGNOR TO RODGER BALLAST CAR COMPANY, A CORPORATION OF MAINE.

RAILWAY-CAR.

1,098,748.

Specification of Letters Patent.

Patented June 2, 1914.

Application filed September 7, 1909. Serial No. 516,394.

To all whom it may concern:

Be it known that I, JOHN O. NEIKIRK, a citizen of the United States, residing at Morgan Park, in the county of Cook and State of Illinois, have invented certain new and useful Improvements in Railway-Cars, of which the following is a specification.

The object of my invention is to improve the construction of cars of the type known as the "Hart convertible Rodger ballast cars." As is well-known, these cars are provided with a central longitudinal hopper, adjustable aprons adapted to form continuations of the hopper walls or to form a flat floor above the hopper, adjustable ends, and doors in the side walls. My improvements are particularly adapted for use in this type of car, but they are not, as will appear from the following description and claims, taken in connection with the drawings, restricted exclusively to this particular type of car.

The particular nature and objects of my invention will be more particularly explained in the following description.

In the drawings—Figure 1 is a transverse section of a car embodying my improvements. Fig. 2 is a longitudinal central section showing the adjustable floor sections raised to form a continuation of the hopper wall. Fig. 3 is a partial side view. Fig. 4 is a detail perspective view showing the side stake construction. Fig. 5 is a detail perspective view of a supporting bracket. Fig. 6 is a view of the same bracket with the hinge members in place. Fig. 7 is a perspective view of a modified form of bracket.

The car illustrated is supported longitudinally upon side sills 1 and intermediate sills 2. Horizontal floor sections 3 extend between the intermediate and side sills, and the hopper 4 is located between the intermediate sills. The floor sections 5 may be adjusted either as shown at the left or the right of Fig. 1 of the drawing. When adjusted as shown at the left of Fig. 1 the floor section 5 rests upon the longitudinal timber 6, and when adjusted as shown at the right the free edge of the section 5, which is pivoted at 7 above the intermediate sill 2, rests against the side stakes of the car.

The hopper comprises a stationary side 8 and the other side is provided with a stationary upper part 9 and a door 10 hinged thereto at 11. One of the objects of my invention is the provision of improved means

for supporting the stationary section 9 and the hinge which supports the hopper door 10. In the present instance I support these parts from the intermediate sill 2, which may be of the plate-girder type. Riveted to the web of the intermediate girder 2 is a bracket 12 which is formed in substantially U-form from a metal plate. The bracket comprises the connecting web 13, the arms 14 bent at right angles thereto, and the flanges 15 which are bent upon lines forming such an angle with the bend between the connecting web 13 and the arms 14 as to give the flange 15 the proper inclination to correspond with the inclination of the hopper. The connecting web 13 is riveted to the girder 2 and the stationary hinge members 16 are bent around the flanges 15 to overlap the same on both sides, and the bend between the two parts of the hinge members 16 is spaced away from the lower edge of the flange 15 in the form of an eyelet to receive the pintle 11 of the hinge. Rivets or bolts 17 pass through the flanges 15, the hinge members 16, the stationary hopper wall 9 and its reinforcing straps 18, thus securely binding together all of the parts referred to. In some instances I prefer to form the bracket as shown in Fig. 7, the flange 13' being designed to be riveted to the girder 2, and the flange 15 to the hopper. When this form of bracket is used, the hinges are preferably bolted to the upper hopper plank on each side of the flange 15 instead of by bolts passing through both the hinge and the bracket flange as in the case of the bracket shown in Fig. 5. The hinge section or door 10 is provided with co-acting hinge members 19 which are also provided with eyelets engaging the pintles 11. The straps 18 upon the upper side of the stationary hopper sections 9 are turned over the upper sides of the intermediate sills 2 and secured thereto, thus affording additional support for the stationary hopper sections 9. The construction above described affords a secure support for the hopper, and one which does not develop defects in use.

Another feature of my improved construction resides in the form of side stake employed. It is necessary that the side stakes be so designed as to support the stationary upper part 20 of the side wall, and it is desirable that the section 20 be continuous and not interrupted at the side stakes. In order

to accomplish this purpose I construct the side stake of two parts, one terminating just beneath and supporting the stationary section 20 of the side wall, and the other bent outwardly and upwardly to engage the outer side of the stationary section. My improved construction is also so designed as to provide appropriate flanges at the sides of the door opening for the doors to close against, thus forming a tight joint. The side stake construction is illustrated in perspective in Fig. 4. The main member of the stake consists of a Z-bar 22 having its inner flange 23 riveted or otherwise secured to the side sill. The Z-bar 22 terminates just beneath and supports the stationary wall section 20. Secured to the web of the Z-bar 22 is an angle iron 24, the inner flange 25 of which lies in the same plane with the inner flange 23 of the Z-bar. The upper end of the angle bar at a point just below the stationary side plank 20 is bent outwardly and upwardly as indicated at 26, thus engaging the outer side of the plank 20 and forming a lateral support therefor. By means of this construction of side stake the stationary side plank 20 is supported both from below and from the outside, and in proper relation to the car underframe. Beneath the upper stationary plank 20 the side stake extends from the inner surface of the side wall outwardly, and opposite the upper stationary plank 20 the side stake extends from the outer surface thereof outwardly, thus permitting the upper plank to extend continuously past the side stakes. This purpose is accomplished according to my invention by a construction which presents ample resistance to the strains imposed by the load in the car and without introducing complicated or expensive forms.

On reference to Fig. 3 it will be observed that the inner flanges 25 of the side stake angle bars project beyond the outer flanges 23 of the Z-bars, thus affording a stop for one edge of each of the doors 28. When the angle irons are all arranged on the same side of the Z-bars the doors 28 will close upon one side against the inner flanges 23 of the Z-bars and on the other side against the inner flanges 25 of the angle bars. For the purpose of holding the side doors 28 closed I have shown a construction now in use comprising a crank shaft 29 journaled in bearings 30 secured to the outer flanges of the Z-bars.

My improved side stake offers a flush surface upon the inside of the car against which the pivoted floor sections 5 rest when raised to the position shown at the right of Fig. 5. The inner surfaces of the side walls are also practically flush, as the side doors 28 when closed rest against the flanges 23 and 24 of the Z-bars and angle bars respectively, as above explained.

As clearly shown in Figs. 1 and 3, the side doors 28 are reinforced by straps 35 bent at their upper ends to form eyelets 36 which receive the hinge pintles 37. The upper stationary side board 20 is rabbeted along its upper outer edge as indicated at 38, and the hinge members 39 are formed with a right angle turn at their upper ends, the horizontal end portion being received in the rabbet or groove 38. By this means the stationary hinge members 39 are securely held in place, and in assemblage an accurate means is afforded for properly positioning the hinge members before riveting or bolting them in place. A horizontal angle iron 40 covers the upper edge of the stationary side board 20 and serves to retain the stationary hinge members 39 in place as well as to protect the side boards from injury.

I claim:

1. In a car of the class described, a longitudinal sill, a hopper, a bracket having a vertical wall secured to said sill and an inclined wall secured to said hopper and a hinge member secured to said bracket and to a stationary part of said hopper.

2. In a car of the class described, longitudinal sills intermediate the center and sides of the car, a hopper depending between said sills, brackets having a vertical wall secured to one of said sills and an inclined wall secured to said hopper and hinge members between and secured to said brackets and hopper.

3. In a car of the class described, longitudinal sills intermediate the center and sides thereof, a hopper depending between said sills, brackets having a vertical web formed to fit the vertical web of one of said sills and an inclined web to fit the inclined wall of said hopper, and hinge members between said brackets and hopper wall, said sill, bracket, hinge member and hopper wall being secured together.

4. In a car of the class described, a vertically disposed longitudinal sill, an inclined hopper wall, a bracket comprising a vertical wall lying against said sill, transverse walls extending from said vertical wall, and inclined flanges on said transverse walls, said inclined flanges being secured to said hopper walls.

5. In a car of the class described, a vertically disposed longitudinal sill, an inclined hopper wall, a bracket comprising a vertical wall lying against said sill, transverse walls extending from said vertical wall, inclined flanges on said transverse walls, said inclined flanges being secured to said hopper wall, and a hinge member lying between and secured to said hopper wall and said flanges.

6. In a car of the class described, a bracket of substantially U-shape and having inclined flanges at the outer ends of the arms

thereof, hinge plates folded around and secured to said flanges, the bends in said plates being spaced from the edges of said flanges to form eyelets to receive a hinge pintle.

7. In a car, a side sill, a side wall comprising a stationary upper section and doors hinged thereto, a side stake comprising one member secured to the side sill and extending upward to said stationary section, and a second member extending upward in alignment with said first member to the lower edge of said stationary section and then bent outwardly and upwardly to lie against the outer surface of said stationary section.

8. In a car, a side sill, a side wall comprising a stationary upper section and doors hinged thereto, side stakes each comprising a Z-bar having one flange secured to said side sill and extending upwardly to the lower edge of said stationary section, an angle bar secured to said Z-bar and having its upper end bent outwardly and upwardly to lie against the outer side of said stationary section.

9. In a car, a side sill, a side wall comprising a stationary upper section and doors hinged thereto, side stakes each comprising a Z-bar having one flange secured to said side sill and extending upward to the lower edge of said stationary section, an angle bar having its inner flange in the plane of the inner flange of the Z-bar except at the upper end where said angle bar is bent outwardly and upwardly to engage the outer surface of said stationary section.

10. In a car, a side sill, side stakes each comprising a Z-bar having its inner flange secured to said side sill, an angle bar having its outer flange secured to the web of said Z-bar, the inner flange of said angle bar extending in the plane of the inner flange of

said Z-bar to a point beyond the outer flange thereof, a side wall comprising a stationary section resting upon the upper ends of said Z-bars, said angle bars extending above said Z-bars and being outwardly and upwardly bent to engage the outer surfaces of said stationary section, and doors hinged to said stationary section and closing against the inner flanges of said Z-bars and angle bars. 50

11. In a car, a side sill, a side wall comprising a stationary upper section and doors hinged thereto, side stakes each comprising a Z-bar having one flange secured to said side sill and extending upward to the lower 55 edge of said stationary section, an angle bar secured to said Z-bar and having its upper end bent outwardly and upwardly to lie against the outer side of said stationary section, and an angle iron secured to the upper 60 ends of said side stake angle bars, said angle iron overlying the top and outer side of said side wall.

12. In a car, a side sill, side stakes each comprising a Z-bar having its inner flange 65 secured to said side sill, an angle bar having its outer flange secured to the web of said Z-bar, the inner flange of said angle bar extending in the plane of the inner flange of said Z-bar to a point beyond the outer flange thereof, a side wall comprising a stationary section resting upon the upper ends of said Z-bars, said angle bars extending above said Z-bars and being outwardly and upwardly bent to engage the outer surfaces 70 75 of said stationary section.

In testimony whereof, I have subscribed my name.

JOHN O. NEIKIRK.
